APPARATUS FOR EXHAUSTING AIR

Original Filed March 5, 1927

UNITED STATES PATENT OFFICE

WILLIAM C. O'LEARY, OF WASHINGTON, DISTRICT OF COLUMBIA

APPARATUS FOR EXHAUSTING AIR

Application filed March 5, 1927, Serial No. 173,204. Renewed August 9, 1928.

This invention relates to an exhausting apparatus, and is designed primarily for exhausting air, but it is to be understood that an exhausting apparatus in accordance with 5 this invention, can be used for any purposes for which it is found applicable, and the invention has for its object to provide, in a manner as hereinafter set forth, for the exhausting of air from an enclosed space to 10 such an extent to create a substantially perfect vacuum therein.

With the foregoing and other objects in view the invention consists of the novel embodiment of an apparatus as hereinafter 15 more specifically described and illustrated in the accompanying drawings, but it is to be understood that changes, variations and modifications relative to the method, as well as to the apparatus, can be resorted to which 20 fall within the scope of the claims hereunto appended.

In the drawings wherein like reference characters denote corresponding parts throughout the several views:

25 Figure 1 is a vertical sectional view of an apparatus in accordance with this invention.

Figures 2 to 5 are vertical sectional views of the apparatus illustrating the sequence of steps when exhausting.

30 Figures 6 and 7 are fragmentary views upon an enlarged scale and in section illustrating details of the apparatus.

The apparatus includes a lower receptacle 2. The receptacle 2 has a rounded top and 35 bottom and provides a chamber 38 for liquid. The receptacle 2 is formed with a valved drain pipe 39 and said receptacle 2 at its top is formed with an opening 40 in which is secured a short vertically disposed, valved, liquid conducting pipe 41, which opens into the bottom of the upper receptacle 3 and the latter provides a chamber 39' for liquid.

The top of the receptacle 3 is formed with 45 an opening 42, which communicates with a stand pipe or liquid receiver 43 of the desired height and which is closed at its top, as indicated at 44. The top 44 of the stand pipe 43 is provided with a pressure gauge 45 which communicates with a valve mechanism 46, an 50 air escape valve device 47 and a valve mecha-

nism 48 which communicates with a suction line 49. The top 44 of the stand pipe 43 is rounded or dome shaped and has its inner face of the same contour as its outer face. The inner face of the top is formed with a 55 pair of spaced concavities, only one of which is shown and is indicated at 43', Figure 6. The valve mechanisms 46 and 47 include a casing 44' which projects outwardly from the rounded top of stand pipe 43. Each casing 60 44' opens into a concavity and has its inner end flush with and forms a continuation of the wall of the latter. See Figure 6. The inner end of casing 44' is provided with a valve seat 45' for a valve 46' carried on the inner end of an adjusting stem 47' which projects from the outer end of the casing 44' and is operated exteriorly of the latter. The pressure gauge 45 opening into the casing 44' of valve mechanism 46 and the pipe or line 49 65 opens into the valve mechanism 48. The air escape valve device 47 is positioned at the highest point of top 44, opens into stand pipe 43 centrally of top 44 and has the valvular element thereof spaced from stand pipe 43. 70 When valves 46' are seated they form continuations of the inner ends of casings 44'. 75

Extending from the bottom of the receptacle 2 to the bottom of the receptacle 3 is a by-pass 50 provided intermediate its ends with the pump element 6. The upper end of the by-pass 50 is provided with a cut-off 51. Communicating with the by-pass 50 in proximity to the receptacle 2 is a liquid supply line 4, formed in proximity to the pump element with a cut-off 52. With reference to Figure 7, the pump element 6 has its cylinder formed by a part of the length of the by-pass 50 and such part of the by-pass is indicated at 54. That part of the by-pass 54 80 which forms the cylinder of the pump element is disposed at an upward inclination and the outer end thereof is so constructed so as not to interfere with the passage of the liquid or rather not to obstruct the passage of the liquid when lifted from the receptacle 2 to the receptacle 3. The pump element 6 further includes a piston 55 provided with check valves 66 which on the inward movement of the piston 55 open for the passage of 85 90 95 100

the liquid through the piston and on the outward movement of the piston, close. The piston when it is reciprocated provides for the lifting of the liquid from the receptacle 2 to the receptacle 3. Connected to the piston 55 and extending from the by-pass 50 is a piston rod 67 which is operated by any suitable means. The by-pass 50 is formed with an extension 68, formed with an opening 69 for the passage of a rod 67. For the purpose of forming a seal-tight joint the extension 68 has connected therewith a cup member 70 which projects therefrom to provide a liquid container 71 adapted to contain a sealing liquid 72. The cup is formed with a valved supply opening 73 and a valved discharge outlet 74 for the purpose respectively of supplying liquid and discharging it from the chamber formed with the cup. The piston rod 67 projects outwardly through the cup 70 and a packing means 74' is mounted in the cup and secured thereto by a gland 75. By this arrangement air is arrested from entering the pumping element 6 during the reciprocation of the piston 55.

25 The liquid is supplied to the receptacles 2, 3, stand pipe and by-pass so as to completely fill the same as shown in Figure 1. After the said elements have been filled the valve 52 is closed. The valve 41 is then closed and 30 the valve 39 opened so that a portion of the liquid in the chamber 38 will be removed and the body of liquid will appear as in Figure 2. The valve 41 is then opened and a portion of the liquid in the chamber 39' is discharged into the chamber 38 as shown in 35 Figure 3 whereby all the liquid is discharged from the stand pipe 43, see Figure 3. After this step the liquid is entirely removed from the receptacle 3 as shown in Figure 4. The 40 receptacles 2 and 3 and stand pipe 43 is then filled with liquid as shown in Figure 2.

Before allowing the liquid to enter the chamber 38 the latter, as well as the chamber 39' and stand pipe 5 are exhausted of air by 45 a pump adapted to be attached to the pipe 47. When the valve 52, in line 4 is opened, as well as the valves 41 and 51, the liquid slowly rises in the receptacles 2, 3, stand pipe 5 and by-pass 50, completely fills the same, and 50 oozes through the escape valve 47 thereby forcing out the air. The valves 41, 51 and 52 are then closed and the drain 39 opened to permit of about two thirds of the liquid to slowly discharge from the chamber 38. 55 The slowly discharging liquid leaves a vacuum space above it amounting to about two thirds the capacity of the chamber 38. The drain 39 is then closed. This operation is the division of a large volume of heavy 60 aerated liquid in a sealed container and the space vacated will be as near a perfect vacuum as is possible, as all the valves and pipe connections are air tight.

The two thirds of the chamber 38 free of 65 the liquid, provides a vacuum which equals

in cubical contents the chamber 39' and the stand pipe. The valve 41 is then opened and the liquid from the stand pipe and chamber 39' falls rapidly into the chamber 38 to the extent to fill two thirds of the chamber 70 38 whereby a vacuum is formed in the stand pipe and the upper portion of the chamber 39', as well as the upper portion of the chamber 38. A further discharge of the liquid from the chamber 39' into the chamber 38 75 will provide for the transferring of the vacuum from the chamber 38 to the chamber 39' and stand pipe 5 and the apparatus will be as shown in Figure 4. A substantially perfect vacuum will then be formed in the 80 standpipe and chamber 39'. Then, by attaching the pipe 49 to an enclosed space, it will be evacuated of air. The exhausted air from the enclosed space which enters the stand pipe and chamber 39' is discharged 85 therefrom by lifting the liquid from the chamber 38 through the by-pass for the purpose of completely filling the chamber 39' and the stand pipe whereby such air will be forced or discharged through the escape 90 valve 47. The pumping element 6 provides for the lifting of the liquid. When the liquid is lifted from the chamber 38 to the chamber 39' the valve 41 is closed. The lifting step of the method is for the purpose of 95 filling the chamber 39' and stand pipe and after completion thereof the apparatus appears as shown in Figure 5, which corresponds to Figure 2. After the air has been exhausted from the chamber 39' and stand 100 pipe, the method is continued so that the apparatus will appear as shown in Figure 3 and then as shown in Figure 4; and when the apparatus, with the liquid, is as shown in Figure 4, the exhausting or rather the 105 exhausting of air from the enclosed space can be had. It will be perceived that the method is a circulating one, with respect to the liquid, and that the liquid never comes in contact with air except at normal pressure infinitesimally at the escape valve.

By repeated rising and falling of the liquid an extremely high vacuum can be obtained in any connected structure, as the method will obtain any result desired short of the absolute. The vacuum in the apparatus constantly is renewed and if any air or gas remains in the liquid after it is de-aerated it would tend to escape into the vacuum space and will be pushed out the escape valve as 110 fast as formed. The liquid will not absorb or become mixed with air because it never comes in contact with air except at the surface when rising and the force of gravity would effectually prevent mixture. The 115 walls of the receptacles would be thick, and would serve a double purpose of resisting the penetration of air and air pressure.

The constructing of the receptacles with rounded tops and bottoms resists air pres- 120

sure. Any air remaining in the receptacles 2, 3, and stand pipe 5 is exhausted therefrom due to the fact that the liquid 13 is supplied in the necessary quantity to completely fill said receptacles 2, 3 and stand pipe 5 and the air which is discharged by the action of the liquid is forced through the escape valve 47. The liquid, during the action of the exhausting air from the receptacles 2, 3, and stand pipe 5 rises slightly above the valvular element of the escape valve mechanism 47 where it acts as a sealing medium and makes the valve mechanism thoroughly efficient to prevent any intake of air in the stand pipe.

It is thought the many advantages of an exhausting apparatus in accordance with this invention can be readily understood, and although the preferred embodiment of the invention is as illustrated and described, yet it is to be understood that changes in the details thereof can be had which will fall within the scope of the invention as claimed.

What I claim is:

1. An air exhausting apparatus comprising a sub-structure containing a liquid supply, a stand pipe arising from the sub-structure and having a rounded top, an escape valve device at the extreme of said rounded top, a valve casing extended from said rounded top and opening into the stand pipe, an exhaust pipe opening into said casing, an exhaust valve operating in said casing for closing the inner end of the latter, means extending into the casing from without for operating the valve, the inner end of said casing and said valve providing when the latter is in closing position a continuation of the inner face of said top, said sub-structure including means for raising and lowering the liquid in the stand pipe to any degree and acting recurrently under control, thereby causing a liquid column to rise and fall in the stand pipe and providing an accurately fitting air pumping piston capable when raised of making complete contact with the top of the stand pipe and the valves for expelling substantially all the air through the escape valve device and when lowered creating a vacuum space substantially free of air.

2. An exhausting apparatus comprising an upper and a lower receptacle impervious to air and adapted to receive a liquid functioning as a piston, a valve controlled pipe for establishing communication between the bottom of the upper and top of the lower receptacle, a valve controlled by-pass impervious to air, communicating with the lower portions of said receptacles and provided with means for elevating the liquid in the upper receptacle, a stand pipe impervious to air, opening at its lower end into said upper receptacle and normally closed at its upper end, escape and suction valve elements at the upper ends of said stand pipe, a liquid con-

ductor leading from a source of supply and opening into said valve controlled by-pass below said means, and a valve controlled drain for said lower receptacle.

3. An exhausting apparatus comprising an upper and a lower receptacle impervious to air and adapted to receive a liquid functioning as a piston, a valve controlled pipe for establishing communication between the bottom of the upper and top of the lower receptacle, a valve controlled by-pass impervious to air, communicating with the lower portions of said receptacles and provided with means for elevating the liquid in the upper receptacle, a stand pipe impervious to air, so opening at its lower end into said upper receptacle and normally closed at its upper end, escape and suction valve elements at the upper end of said stand pipe, a liquid conductor leading from a source of supply and opening into said valve controlled by-pass below said means, and a valve controlled drain for said lower receptacle, said conductor having a closure valve near each end thereof.

4. An exhausting apparatus comprising an upper and a lower receptacle adapted to receive a liquid, a valve controlled pipe interposed between said receptacles for establishing communication therebetween, a stand pipe opening at its lower end into said upper receptacle, adapted to receive the liquid from the latter and normally closed at its upper end, escape and suction valve elements at the upper end of said stand pipe, a valve controlled means for elevating the liquid from the lower to the upper receptacle, a valve controlled liquid conducting means for opening into said valve controlled means for supplying liquid thereto, said valve controlled pipe provided for the discharge of liquid from the stand pipe into the upper receptacle and from the latter into the lower receptacle to form a vacuum in the stand pipe and upper receptacle for exhausting air from a closed space through said suction element to provide a substantially perfect vacuum in said space, and said lower receptacle provided with a valve controlled drain pipe.

5. An air exhausting apparatus comprising a sub-structure containing a liquid supply, a stand pipe for receiving liquid from said sub-structure and closed at its upper end, a controllable, valved air escape device communicating with said stand pipe through the top thereof and having its valve element positioned exteriorly of the inner face of said pipe, a suction line controllable device of the valved type communicating with said pipe through the top thereof and having its valve element arranged exteriorly of the inner face of said pipe, said valve elements positioned in the path of the liquid supplied to said pipe, means within the sub-structure for raising the liquid into the stand pipe to any degree required, and means for lowering the

- liquid from the stand pipe, the said means acting recurrently under control, thereby providing an accurately fitting air pumping piston from said liquid capable of making complete contact with the inner face of the top of the stand pipe and with said valve elements for respectively expelling substantially all air through the air escape device and for creating a vacuum space in said pipe substantially free of air.
6. An air exhausting apparatus comprising a sub-structure containing a liquid supply, a stand pipe for receiving liquid from said sub-structure and closed at its upper end, a controllable, valved air escape device communicating with said stand pipe through the top thereof and having its valve element positioned exteriorly of the inner face of said pipe, a suction line controllable device of the valved type communicating with said pipe through the top thereof and having its valve element arranged exteriorly of the inner face of said pipe, said valve elements positioned in the path of the liquid supplied to said pipe, means within the sub-structure for raising the liquid into the stand pipe to any degree required, and means for lowering the liquid from the stand pipe, the said means acting recurrently under control, thereby providing an accurately fitting air pumping piston from said liquid capable of making complete contact with the inner face of the top of the stand pipe and with said valve elements for respectively expelling substantially all air through the air escape device and for creating a vacuum space in said pipe substantially free of air, the inner face of said stand pipe at its top being rounded, said air escape device being positioned centrally of the top of the stand pipe, said exhaust conducting device positioned at the top of the stand pipe adjacent the air escape device.
7. An air exhausting apparatus comprising a sub-structure containing a liquid supply, a stand pipe for receiving liquid from said sub-structure and closed at its upper end, a controllable, valved air escape device communicating with said stand pipe through the top thereof and having its valve element positioned exteriorly of the inner face of said pipe, a valve housing extending outwardly from the top of and opening into said pipe, said casing having its inner end provided with a valve seat, a suction valve element operating against said seat for closing the housing to the pipe, a controllable rod for and carrying the second valve element and projecting outwardly from said housing, an exhaust conducting line opening into said housing, the inner end of said housing being flush with the inner face of said pipe, the valve element in said housing being flush, when seated with the inner end of said housing, said valve elements positioned in the path

of the liquid supplied to said pipe, means within the substructure for raising the liquid into the stand pipe to any degree required, and means for lowering the liquid from the stand pipe, the said means acting recurrently under control, thereby providing an accurately fitting air pumping piston from said liquid capable of making complete contact with the inner face of the top of the stand pipe and with said valve elements for respectively expelling substantially all air through the air escape device and for creating a vacuum space in said pipe substantially free of air.

In testimony whereof, I affix my signature hereto.
